PRESELECTOR SYSTEM

Dwight V. Sinnerger, Chicago, Ill., assignor to
 Johnson Laboratories, Inc., Chicago, Ill., a
 corporation of Illinois

Application February 11, 1936, Serial No. 63,295

12 Claims. (Cl. 250—20)

The invention relates to high-frequency circuits and more particularly to those employed in receiving systems of the superheterodyne type, where the signal passes through several circuits 5 tuned to the signal frequency, is modulated with locally produced oscillations, then is demodulated and amplified at an intermediate frequency, and finally is demodulated again and rendered audible. The part of the system through which the 10 signal passes without a change in frequency usually includes an antenna circuit and one or two resonant circuits with or without a thermionic amplifier tube, and may be termed the "pre-selector".

The selectivity obtainable in a superheterodyne 15 system is largely due to the efficiency of the intermediate-frequency amplifier which, being operated at a fixed frequency, may be designed to have a desired selectivity characteristic. The pre-selector of the receiving system serves to collect 20 the desired signal, to aid in the rejection of undesired signals in adjacent channels, and to substantially reject signals of certain other frequencies to which a superheterodyne receiver 25 tends to respond.

One of the objects of the invention is to provide a simple, inexpensive, and efficient system of pre-selection. Another object of the invention is to so shape the selectivity characteristic of the 30 pre-selector that the receiver is particularly adaptable for high-fidelity reception, that is, not discriminatory against the higher modulation frequencies of the incoming signal. Still another object of the invention is to produce a sufficiently 35 great signal gain between the antenna and the input to the first demodulator as to insure a high signal-to-noise ratio. A further object of the invention is to improve the image-frequency ratio of a superheterodyne receiver and to sufficiently 40 reject signals of the intermediate frequency of the receiver.

The invention will be better understood if reference is made to the accompanying drawing, in which:

Fig. 1 is a block diagram of a superheterodyne radio receiver;

Fig. 2 is a schematic diagram of the pre-selector of a superheterodyne radio receiver embodying the invention; and

Fig. 3 is a schematic diagram of a modified form of pre-selector embodying the invention.

Referring to Fig. 1, the block diagram schematically shows the components of a superheterodyne receiver. The signal received on the antenna is fed through a pre-selector, which may

or may not include a vacuum-tube amplifier, to the first demodulator. The demodulator is supplied by the local oscillator with oscillations of such frequency that the resultant beat frequency is equal to the resonant frequency of the intermediate-frequency amplifier. The beat-frequency signal is amplified and passed through the second demodulator, where it is rectified to produce an audible component which, after suitable amplification, is delivered to the loud speaker. 10

Referring to Fig. 2, the antenna 1 is connected to ground through a high-impedance choke coil 2 and is coupled by means of capacitor 3 to the tuned circuit 4. Circuit 4 includes iron-core inductor 5, variable tuning capacitor 6, adjustable trimmer capacitor 7, coupling winding 9, and coupling capacitor 11. Tuned circuit 8 includes iron-core inductor 5a, which is inductively coupled to winding 9, variable tuning capacitor 6a, adjustable trimmer capacitor 7a, and coupling 20 capacitor 11. Circuit 8 is in the input circuit 25 of vacuum tube 10, which is arranged to function as the first demodulator of a superheterodyne receiver. The junction of inductor 5a and capacitor 11 is normally connected to a source of 25 biasing potential, which may, for example, be provided by an automatic amplification control resistor in the output circuit of the second demodulator.

Inductors 5 and 5a are preferably of the type 30 which is made by employing a sectionalized winding of Litz wire on a core of finely comminuted magnetic material. The high efficiency of this type of inductor permits high gain to be obtained between antenna 1 and circuit 4 with a coupling 35 capacitor 3 of relatively low capacitance, so that changes in the electrical characteristics of antenna 1 have a relatively small effect upon the resonant frequency of circuit 4. Choke coil 2 is 40 preferably of sufficiently high inductance so that the resonant frequency of the antenna circuit 45 is below the lowest frequency to which circuit 4 may be tuned, but higher than the intermediate frequency to be employed in the receiver, in order to improve the performance at the lower 45 signal frequencies without increasing the response of the receiver to undesired signals of the intermediate frequency.

Winding 9 is so related in number of turns and 50 spacing with respect to inductor 5a that the inductive coupling between the winding and the inductor is slightly greater than optimum. This over-coupling produces a desired broadening of the selectivity characteristic of the pre-selector without appreciably affecting the steepness of the 55

sides of the characteristic. It is in this manner that attenuation in the pre-selector of the higher modulation frequencies of the incoming signal is avoided. Capacitor 11 has such a large capacitance that the coupling between circuits 4 and 8 is substantially entirely inductive at signal frequencies, as for example between 540 and 1600 kilocycles. With this arrangement, it is possible to realize, from the antenna to the grid of vacuum tube 10, substantially half of the gain obtained between the antenna and the circuit 4. Circuits 4 and 8 may be simultaneously tuned to the frequency of the desired signal by mechanically ganging variable capacitors 6 and 6a.

15 When the usual superheterodyne radio receiver is tuned to a desired signal, some response is likely to be obtained from a second signal which is higher in frequency than the desired signal by twice the intermediate frequency of the receiver.

20 The undesired signal may be called the image-frequency signal. For example, if the desired signal has a frequency of 600 kilocycles and the intermediate frequency of the receiver is 450 kilocycles, the image-frequency signal will have a frequency of $600 + (2 \times 450)$ or 1500 kilocycles. The ratio of the input voltage of image frequency required to produce a given output to the signal voltage required for the same output is called the image-frequency ratio. In the usual receiver

25 which employs two tuned circuits in the pre-selector, the image-frequency ratio may be of the order of 3000. A feature of the present invention is to substantially raise the value of this ratio by the proper selection and arrangement of the circuit components.

30 Referring again to Fig. 2, circuit 4, which is tuned to the frequency of the desired signal, appears as a reactance to the image-frequency signal, and in itself offers an image-frequency ratio of about 50 to 60. Circuit 8, being also tuned to the frequency of the desired signal, likewise offers an image-frequency ratio of the same order, so that the over-all image-frequency ratio of the pre-selector is about 3000. In addition, a portion of the image-frequency signal is shunted to ground through capacitor 7 and winding 9. This flow of image-frequency current through winding 9 induces in inductor 5a a voltage of image frequency which is opposite in phase to the image-frequency voltage normally present at the terminals of inductor 5a. By proper choice of capacitor 7, the image-frequency ratio of the receiver may be increased by this method to a value of the order of 10,000 to 50,000. Alternatively, capacitor 7 may be connected as shown in Fig. 3 directly between the antenna 1 and the high-potential terminal of winding 9. This arrangement minimizes the effect which capacitor 7 has on the tuning range of variable capacitor 6.

35 The gain of the pre-selector is largely dependent upon the proper design of the antenna circuit. The nearer the resonant frequency of the antenna circuit is to the lower limit of the signal frequencies, the higher the gain obtainable. The lowest frequency of the broadcast band is about 540 kilocycles, and the intermediate frequency is usually about 450 kilocycles. The resonant frequency of the antenna circuit should be so chosen, by proper selection of inductor 2, that the antenna circuit will resonate at a frequency between 450 and 540 kilocycles. If the antenna circuit resonates too near the intermediate frequency of the receiver, a signal of the intermediate frequency intercepted by the antenna may

be amplified by the receiver, thus producing an undesired response. A feature of the present invention is to substantially suppress this undesired signal.

Again referring to Fig. 2, capacitor 11, which is common to circuits 4 and 8, provides capacitive coupling between the two circuits which is in opposition to the inductive coupling between winding 9 and inductor 5a. The capacitance of coupling capacitor 11 is so chosen that, at the intermediate frequency of the receiver, the inductive and capacitive couplings between circuits 4 and 8 are substantially equal and therefore balance each other out. As the frequency increases, however, the inductive coupling becomes greater and the capacitive coupling decreases, so that in the signal-frequency range the coupling is substantially entirely inductive. In a particular instance, a receiver embodying the present invention was tuned to a signal frequency of 600 kilocycles. The undesired response to a signal of 450 kilocycles, the intermediate frequency of the receiver, increased ten times when the arrangements of the invention were rendered inoperative without otherwise altering the receiver. The addition of the arrangements herein described produced only a slight decrease in the gain of the receiver at the lower signal frequencies.

By applying the teachings of the present invention, it is possible to design a pre-selector having high gain, a high signal-to-noise ratio, a high image-frequency ratio and good attenuation of intermediate-frequency signals, with the use of only two variably tuned circuits. Furthermore, a pre-selector designed in accordance with the invention provides freedom from serious attenuation of the higher modulation frequencies of the incoming signal.

Having thus described my invention, what I claim is:

1. A pre-selector system for a superheterodyne receiver including a fixed-tuned antenna circuit and a pair of variably tunable resonant circuits, a capacitance connected between said antenna and one of said resonant circuits, means including an inductance for coupling said resonant circuits, variable capacitors for tuning said resonant circuits and adjustable capacitors for aligning said resonant circuits, one of said adjustable capacitors being so connected to said inductance as to increase the discrimination of said system against signals of image frequency.

2. A pre-selector system for a superheterodyne receiver having an intermediate-frequency amplifier, said system including an antenna circuit and first and second resonant circuits, combined inductive and capacitive coupling means between said antenna and said first resonant circuit, said antenna circuit including a reactor such that the natural frequency of said antenna circuit is lower than any frequency to which said resonant circuits are tunable but higher than the frequency of said intermediate-frequency amplifier, and inductive-capacitive coupling means between said first and second resonant circuits, said last-mentioned coupling means being adapted to exclude signals of the frequency of said intermediate-frequency amplifier.

3. A pre-selector system for a superheterodyne receiver having an intermediate-frequency amplifier, said system including an antenna circuit and first and second resonant circuits, combined inductive and capacitive coupling means between said antenna and said first resonant circuit, said

5 antenna circuit including a reactor such that the natural frequency of said antenna circuit is lower than any frequency to which said resonant circuits are tunable but higher than the frequency 5 of said intermediate-frequency amplifier, inductive-capacitive coupling means between said first and second resonant circuits, said last-mentioned coupling means being adapted to exclude signals of the frequency of said intermediate-frequency 10 amplifier, and capacitance between said antenna circuit and said last-mentioned coupling means to increase the discrimination of said system against signals of image frequency.

15 4. A pre-selector system for a superheterodyne receiver having an intermediate-frequency amplifier, said system including an antenna circuit and first and second resonant circuits, variable capacitors for tuning said resonant circuits and adjustable capacitors for aligning said resonant 20 circuits, combined inductive and capacitive coupling means between said antenna and said first resonant circuit including a reactor such that the natural frequency of said antenna circuit is lower than any frequency to which said resonant 25 circuits are tunable but higher than the frequency of said intermediate-frequency amplifier, inductive-capacitive coupling means between first and second resonant circuits, said last-mentioned coupling means being adapted to exclude signals of the frequency of said intermediate-frequency 30 amplifier, one of said adjustable capacitors being connected to said last-mentioned coupling means to increase the discrimination of said system against undesired signals which differ in frequency from the desired signal by twice the 35 frequency of said intermediate-frequency amplifier.

40 5. A pre-selector system for a superheterodyne receiver having an intermediate-frequency amplifier, said system including an antenna circuit and first and second resonant circuits, each of said resonant circuits having a high-potential side and a low-potential side, variable capacitors connected from the high-potential sides of said 45 resonant circuits to ground for tuning said resonant circuits adjustable capacitors connected from the high-potential sides to the low-potential sides of said resonant circuits to align said resonant 50 circuits, combined inductive and capacitive coupling means between said antenna and said first resonant circuit including a reactor such that the natural frequency of said antenna circuit is lower than any frequency to which said resonant 55 circuits are tunable but higher than the frequency of said intermediate-frequency amplifier and a winding inductively coupled to said second resonant circuit connected in series with a fixed capacitor between the low-potential side of said 60 first resonant circuit and ground.

65 6. A pre-selector system for a superheterodyne receiver having an intermediate-frequency amplifier, said system including an antenna circuit and first and second resonant circuits, each of said resonant circuits having a high-potential side and a low-potential side, variable capacitors connected from the high-potential sides of said resonant 70 circuits to ground for tuning said resonant circuits, an adjustable capacitor connected from the high-potential side to the low-potential side of said second resonant circuit to align said resonant circuit, combined inductive and capacitive coupling means between said antenna and said first resonant circuit including a reactor such that the natural frequency of said antenna 75

circuit is lower than any frequency to which said resonant circuits are tunable but higher than the frequency of said intermediate-frequency amplifier, a winding inductively coupled to said second resonant circuit connected in series with a fixed 5 capacitor between the low-potential side of said first resonant circuit and ground, and an adjustable capacitor connected between said antenna and the low-potential side of said first resonant circuit. 10

15 7. A pre-selector system for a superheterodyne receiver having an intermediate-frequency amplifier, said system including an antenna circuit and first and second resonant circuits, combined inductive and capacitive coupling means between said antenna and said first resonant circuit, said antenna circuit including a reactor such that the natural frequency of said antenna circuit is lower than any frequency to which said resonant 20 circuits are tunable, and inductive-capacitive coupling means between said first and second resonant circuits, said last-mentioned coupling means being adapted to exclude signals of the frequency of said intermediate-frequency amplifier. 25

30 8. A pre-selector system for a superheterodyne receiver having an intermediate-frequency amplifier, said system including an antenna circuit and first and second resonant circuits, combined inductive and capacitive coupling means between said antenna and said first resonant circuit, said antenna circuit including a reactor such that the natural frequency of said antenna circuit is lower than any frequency to which said resonant 35 circuits are tunable, inductive-capacitive coupling means between said first and second resonant circuits, said last-mentioned coupling means being adapted to exclude signals of the frequency of said intermediate-frequency amplifier, and capacitance between said antenna circuit and said last-mentioned coupling means to increase the discrimination of said system against signals of image 40 frequency.

45 9. A pre-selector system for a superheterodyne receiver having an intermediate-frequency amplifier, said system including an antenna circuit and first and second resonant circuits, variable capacitors for tuning said resonant circuits and adjustable capacitors for aligning said resonant circuits, combined inductive and capacitive coupling means between said antenna and said first resonant circuit including a reactor such that the natural frequency of said antenna circuit is lower than any frequency to which said resonant 50 circuits are tunable, inductive-capacitive coupling means between said first and second resonant circuits, said last-mentioned coupling means being adapted to exclude signals of the frequency of said intermediate-frequency 55 amplifier, one of said adjustable capacitors being connected to said last-mentioned coupling means to increase the discrimination of said system against undesired signals which differ in frequency from the desired signal by twice the frequency of said intermediate-frequency 60 amplifier.

65 10. A pre-selector system for a superheterodyne receiver having an intermediate-frequency amplifier, said system including an antenna circuit and first and second resonant circuits, each of said resonant circuits having a high-potential side and a low-potential side, variable capacitors connected from the high-potential sides of said resonant 70 circuits to ground for tuning said resonant circuits, adjustable capacitors connected from the high-potential sides of said resonant circuits to the low-potential sides of said resonant circuits to align said resonant circuits, combined inductive and capacitive coupling means between said antenna and said first resonant circuit including a reactor such that the natural frequency of said antenna 75

ed from the high-potential sides to the low-potential sides of said resonant circuits to align said resonant circuits, combined inductive and capacitive coupling means between said antenna and said first resonant circuit including a reactor such that the natural frequency of said antenna circuit is lower than any frequency to which said resonant circuits are tunable and a winding inductively coupled to said second resonant circuit connected in series with a fixed capacitor between the low-potential side of said first resonant circuit and ground. 10

11. A pre-selector system for a superheterodyne receiver having an intermediate-frequency amplifier, said system including an antenna circuit and first and second resonant circuits, each of said resonant circuits having a high-potential side and a low-potential side, variable capacitors connected from the high-potential sides of said resonant circuits to ground for tuning said resonant circuits, an adjustable capacitor connected from the high-potential side to the low-potential side of said second resonant circuit to align said resonant circuit, combined inductive and capacitive coupling means between said an- 25

tenna and said first resonant circuit including a reactor such that the natural frequency of said antenna circuit is lower than any frequency to which said resonant circuits are tunable, a winding inductively coupled to said second resonant circuit connected in series with a fixed capacitor between the low-potential side of said first resonant circuit and ground, and an adjustable capacitor connected between said antenna and the low-potential side of said first resonant circuit. 10 5

12. A preselector system for a superheterodyne receiver including a fixed-tuned antenna circuit and a pair of resonant circuits each having variable tuning capacitance, one of said resonant circuits having first and second serially connected but magnetically uncoupled inductors, the first of said inductors being coupled to said antenna circuit the second of said inductors being inductively coupled to the other of said resonant circuits, and a capacitor so connected between said antenna circuit and the junction of said inductors and so proportioned as to materially increase the discrimination of said system against signals of image frequency. 20
